BOWLING BALL SUPPORT

Wesley Harrigan, Milwaukee, Wis.

Application August 17, 1940, Serial No. 353,040

2 Claims. (Cl. 248—350)

This invention relates to supports for bowling balls and the like.

No provision has heretofore been made for the adequate care of a selected or privately owned bowling ball while the bowler is awaiting his opportunity to start a game. As a consequence he is confronted with the burdensome task of holding his heavy ball in his arms or of keeping it in place on the floor or bench beside him. Unless held, it is liable to damage and likely to roll away.

One object of the present invention is the provision of an individual bowling ball support capable of retaining the ball in any selected location or place of deposit.

Another object is to provide an individual bowling ball support capable of releasable adherence to the ball so as to be carried by the ball when the latter is moved from one place of deposit to another.

Another object is to provide a bowling ball support of a size and shape for convenient handling and for deposit in the pocket when not in use.

Other more specific objects and advantages will appear from the following description of a bowling ball support embodying the present invention.

In the accompanying drawing:

Figure 1 is a transverse sectional view on the line 1—1 of Fig. 2 of a bowling ball support constructed in accordance with the present invention.

Fig. 2 is a plan view.

Fig. 3 is a transverse sectional view of the support, shown applied to a bowling ball.

The bowling ball support shown comprises a flexible web 10 of rubber or like resilient material fashioned to provide an upper concave face 11 having a radius of curvature less than that of the ball a to be supported. The face 11 preferably terminates in a continuous flexible peripheral lip 12 adapted to closely conform to the surface of the ball and to thereby seal the space between the face 11 and the ball. By compressing the web 10 toward or against the ball, air is excluded from the space therebetween, thereby establishing a partial vacuum therein, causing the web 10 and lip 12 to adhere by suction to the face of the ball.

An appropriate mounting base is also provided so related to the web 10 as not to interfere with the suction inducing function thereof. Such a base is shown at 13 disposed to support the web

along its outer margin and preferably comprising a relatively thick ring formed integral with the web. The external diameter or spread of the base 13 is such as to provide a stable support for the ball resting thereon.

The center 14 of the web 10 is preferably disposed to normally project below the bottom of the base 13 so that the web is automatically flexed upwardly into suction producing position, by the 10 supporting surface on which it rests, whenever the ball is deposited on the support. This action is ordinarily sufficient to cause the support to cling to the ball when the latter is lifted, but the grip thereof upon the ball may be increased, if desired, 15 by additional flexing pressure manually applied to the under side of the web. In any event the grip is never such as to prevent ready removal from the ball whenever desired.

As may be noted from a comparison with the 20 ball in Fig. 3, the support is not large but of a size for convenient handling and readily insertable into the pocket when not in use.

Various changes may be made in the embodiment of the invention hereinabove specifically described without departing from or sacrificing the advantages of the invention as defined in the appended claims.

I claim:

1. A bowling ball support comprising a concave 30 cup having a circular marginal portion for sealing contact with said ball, a downwardly projecting ring underlying said marginal portion, said ring terminating substantially in the plane of the central bottom surface of said cup, when said ball is 35 disposed upon said cup, and forming a support for said cup.

2. A bowling ball support comprising a relatively shallow resilient cup of less diameter than the ball and having a ball receiving cavity defined by 40 an arc having a radius less than the radius of the ball, said cup having a circular marginal portion for sealing contact with the ball, and means extending downwardly from and underlying said marginal portion to support said cup and ball, said cup also having an intermediate bottom portion distortable toward the ball and thereby tensionable to induce a suction grip between said cup and ball.

WESLEY HARRIGAN.
